UNITED STATES PATENT OFFICE.

CHRISTIAN RASMUSSEN, OF CLEVELAND, OHIO.

ELECTRIC-CIRCUIT MAKER AND BREAKER.

1,312,208.

Specification of Letters Patent. Patented Aug. 5, 1919.

Application filed March 26, 1919. Serial No. 285,192.

To all whom it may concern:

Be it known that I, CHRISTIAN RASMUSSEN, citizen of the United States, residing at Cleveland, in the county of Cuyahoga and State of Ohio, have invented certain new and useful Improvements in Electric-Circuit Makers and Breakers, of which the following is a specification.

This invention relates to an improvement in electric circuit makers and breakers, and more particularly in the electrical contact finger shown and described in my Letters Patent No. 1,276,110, dated August 20, 1918. In the present device I seek to make a simple organization of parts adapted to afford a rotatable union which may be conveniently assembled and disassembled while effecting a secure and safe locking of the members when assembled without any jutting or projecting parts at the sides.

In the drawing accompanying this application, Figure 1 is a plan view, partly in section, of my improved electrical contact device; and Fig. 2 is a side elevation, with a part broken away, of the same organization of parts. Figs. 3 to 7 inclusive, are detail views of the bracket, the spring, the locking washer, the finger barrel and the pivot screw, respectively.

The conception involves the use of a bracket 2 upon which a finger 3 is rotatably mounted and adapted to oscillate under the tension of a coiled spring 4. The outer end of finger 3 is equipped with a replaceable contact member 5 locked in place by a nut 6, and a set screw 7 mounted upon the finger limits the movement of the finger in one direction. The parts described, are in general substantially the same as shown in my patented structure, but the mode of uniting the parts is quite different and more desirable and efficient. Thus, bracket 2 comprises a vertical flange 8 having an integral hub 9 with a central screw-threaded opening 10 adapted to receive a pivot screw 11, and finger 3 comprises a round barrel or base cap 12 adapted to inclose hub 9 and spring 4 and having a countersunk opening in its flat side wall 14 adapted to seat the flaring head 15 of screw 11. A short straight cylindrical shoulder portion 16 on screw 11 at the base of its flaring head 16 is also en-

gaged with wall 14 to provide an additional journal bearing, and a short annular shoulder 17 upon one side of bracket flange 8 is also engaged within the opposite open side of the barrel or cap to provide a journal bearing of substantial diameter but not of any great length so as to promote free turning. The coiled spring 4 has its opposite ends bent and engaged with the flange 8 and wall 14, respectively, to exert a constant tension upon the finger to hold it to its work, and in use the finger oscillates and turns upon the pivot screw 11 and the screw is liable to become loose. To overcome this objection and the troubles incident thereto, the round boss or hub 9 is made of a predetermined length to permit a split locking washer 18 to be used between the flat end of the hub and the base side of the enlargement or shoulder portion 16 of screw 11, and when the screw is tightened and screwed into the boss or hub to its maximum a slight space remains between the outer face of the washer and the inner surface of wall 14 and the spring pressing endwise upon the wall maintains this working relation and prevents the washer from being engaged and disturbed in its locked setting. The barrel or cap also covers and conceals the locking and working parts except the slotted face of the screw head 15, and when the parts are secured together a free working assembly is had and the established working relationship is permanent.

The oscillatory movement of finger 3 is also limited by a lug 19 at the open side of the cap operating in a notch or recess 20 in the edge of flange 8, and this limiting stop is more especially intended to prevent the finger from being turned back too far and straining or injuring the spring.

What I claim is:

1. In a device as described, a bracket, a contact finger having a recessed pivot end, a pivot screw for said finger, and a locking device for said pivot screw inclosed within and covered by said recessed end of said finger.

2. In a device as described, a bracket having an integral boss with a screw-threaded opening, a spring coiled about said boss, a contact finger having a cap sleeved over

said boss and spring, and a pivot screw for said finger having a locking device therefor confined within said cap.

3. In a device as described, a bracket having a round boss and a contact finger having a cap portion rotatably mounted upon said bracket, a pivot screw extending through said cap portion into said boss, a

locking washer interposed between said screw and said boss, and a coiled spring ¹⁰ adapted to turn said finger and press the cap apart from said washer.

Signed at Cleveland, in the county of Cuyahoga, and State of Ohio, this 22nd day of March, 1919.

CHRISTIAN RASMUSSEN.
